UNITED STATES PATENT OFFICE

149,484

DESIGN FOR AN EMBROIDERED LACE

Abe Gelb, New York, N. Y.

Application September 4, 1947, Serial No. 141,204

Term of patent 3½ years

(Cl. D47—6)

To all whom it may concern:

Be it known that I, Abe Gelb, a citizen of the United States of America, residing in New York city, county of New York and State of New York, have invented a new, original, and ornamental Design for an Embroidered Lace, of which the following is a specification, reference being had to the accompanying drawing, forming part thereof, wherein the figure is a plan view of a piece of embroidered lace, showing my new design.

The background of the embroidered lace is partially omitted for convenience in illustration.

I claim:

The ornamental design for an embroidered lace, substantially as shown and described.

ABE GELB.
